UNITED STATES PATENT OFFICE.

JOHN C. WAHL, OF CHICAGO, ILLINOIS, ASSIGNOR, BY MESNE ASSIGNMENTS, TO REMINGTON ACCOUNTING MACHINE CORPORATION, OF NEW YORK, N. Y., A CORPORATION OF NEW YORK.

CALCULATING-MACHINE.

1,400,584.

Specification of Letters Patent. Patented Dec. 20, 1921.

Application filed March 20, 1917. Serial No. 156,009.

To all whom it may concern:

Be it known that I, JOHN C. WAHL, a citizen of the United States, residing at Chicago, in the county of Cook and State of Illinois,

5 have invented certain new and useful Improvements in Calculating-Machines, of which the following is a specification.

My invention is an improved adding and subtracting machine designed for the listing 10 and computation of numbers and is of the class in which there is a totalizer and a master wheel adapted to enter numbers therein one digit at a time. The master wheel is connected by differential mechanism to a set 15 of ten numeral keys any of which, when operated determines the extent of rotation of the master wheel and consequently the number inserted in the totalizer.

The decimal relation of the master wheel 20 to the totalizer is controlled by an escape- ment device which shifts said wheel step by step upon the actuation of any of the numeral keys. Before entering a number in the totalizer, it is necessary to tabulate the 25 master wheel so that it will be in coöperation with the decimal order of the totalizer corresponding to the highest digit of the number to be subsequently inserted. To this end suitable tabulating mechanism for the mas- 30 ter wheel has been provided. Numbers in- serted into the totalizer digit by digit are printed when inserted and to this end I have provided a set of type bars and mechanism under the control of the numeral keys to op- 35 erate said bars. This mechanism is so con- structed that the action of the key stores up power sufficient to operate its associated type bar and when the key has reached a pre- determined position this stored power is re- 40 leased and brought into action and the type bar is operated by it irrespective of any fur- ther motion on the part of the key.

My herein described machine is also adapt- 45 ed to subtract numbers as well as add them and to this end I have provided a reversing device for the master wheel to determine the direction of rotation thereof consequent on the operation of any of the numeral keys. This reversing device is controlled by a suit- 50 able lever and coincidently with the rever-

sal of the machine, the ribbon associated with the type bars is shifted so that subtracted numbers will be printed in a different color.

The platen of my improved machine is 55 arranged to be shifted step by step with the master wheel as the numbers are entered one digit at a time and I have arranged the tabulating mechanism so that a single tabulating mechanism operates simultaneously upon 60 both the master wheel and the platen. As a result of this arrangement the operation of a single tabulating key brings the platen into the proper position to receive the first digit of the subsequently entered number and also 65 brings the master wheel in a position to enter said number in its proper place in the totalizer.

The platen is tabulated prior to the inser- 70 tion of each number and I have therefore, arranged the paper feed mechanism which serves to space the platen line by line to be operated by, and coincidently with, the op- eration of the tabulating mechanism.

In general, the operation of my machine is 75 that when it is desired to enter a number therein, the platen and master wheel are first tabulated to the position of the highest digit of said number by means of one 80 of the tabulating keys. The number is then entered digit by digit by means of the numeral keys, the platen and master wheel spacing step by step in the opposite direction as the keys are successively de- pressed. When it is desired to enter a new 85 number, the tabulator key is again operated which action spaces the platen to the next line and re-locates the master wheel and platen in their proper positions to enter and print the next number to be inserted. 90

In general, the object of my invention is to provide an improved mechanism for car- 95 rying out the various operations and func- tions above set forth.

More particularly one of the objects of my invention is to provide a calculating ma- chine with a traveling platen and a traveling decimal carriage connected therewith and providing improved tabulating means to lo- 100 cate positively both the tabulator and the

platen by means of a single operation of a tabulator key.

A further object of my invention is the provision of an interlock between the tabulating and numeral keys, whereby when one key of either set is being operated it will be impossible to operate any of the other keys until the operation which has just been initiated is completed.

10 A further object of my invention is the provision of a platen operated by a force-feed escapement operating in conjunction with my improved tabulating device as above set forth.

15 A still further object of my invention is the provision of what I may term a stored power printing mechanism in combination with a machine of the type described. This mechanism will be fully set forth in the specification and I shall not further elaborate on it.

Another object of my invention is the provision of a traveling decimal carriage which contains certain calculating elements, such 25 as a master wheel, a master dog, pawls for accurately locating the master wheel, etc., and connecting such a carriage to a traveling platen in a manner to cause the carriage and platen to travel in reverse directions.

30 A further object of my invention is the construction of a calculating machine in which the various calculating units required for the functioning of a machine as a whole are mounted in independent supports and then these supports are united by a common framework. In my improved machine herein described, the totalizer is an independent unit, as is likewise the master element for 35 operating the same. The differential mechanism for operating the master mechanisms is mounted in an independent framework, and any one of these mechanisms may be adjusted to perform its function correctly 40 without the necessity of assembling the mechanism in the complete machine. Further the platen, platen-rotating and feeding means are contained in a single structural unit. The printing means are also contained in a single unit and said units may 45 be adjusted separately before they are united by the common supporting framework. Many advantages result from my herein described structural arrangement, since the 50 various units which are necessary to complete a machine may be assembled and tested in different departments before they are brought together for their final assemblage in the complete calculating machine.

55 60 Another object of my invention is the provision of a machine printing on a strip of paper most conveniently arranged in a roll, supporting this roll from the framework of the machine and leading the strip of paper 65 over a guide to a movable platen. By this

expedient I avoid the necessity of having to shift a heavy paper roll, step by step on one hand, of having to shift a type basket step by step on the other.

Another object of my invention is the provision of line spacing means operating in conjunction with the tabulating mechanism. It will be remembered from the previous description that before entering a number in my improved machine, it is necessary to 70 tabulate the platen to the proper decimal position. I have arranged the paper feed for the platen so that the act of tabulating the platen will space the same to the next 75 line of writing.

80 The above and many other objects of my invention will be more fully set forth in the following specification and claims, and the advantages of my herein described machine over those of the prior art will be apparent 85 to those skilled in the calculating machine art:

My invention may be best understood by reference to the accompanying drawings, of which—

Like numerals are applied to the same parts in all the figures.

My machine is composed of an assemblage of independent units having but few points 15 of connection with each other. Each of these units is supported in an independent framing which in its turn is supported between two outside plates 50 and 51. The separate units of which my machine is composed are: 1st: the totalizer unit; 2nd: the actuator unit; 3rd: the printing unit; 4th: the platen unit, and 5th: the numeral and tabulator keys and parts of the tabulating mechanism which are swung directly between the side plates 50 and 51.

The actuator unit comprises structurally a casting 52, Fig. 2, to which are attached the side plates 53 and 54. The casting 52 has integral with it the rearwardly extending lugs 55 and 56, which serve to support the ribbon spools and the ribbon feeding mechanism. Swung between the side plates 50 and 51 at the back portion of the machine, is a casting 57, which serves to support the type bars for printing the numbers and also a portion of the ribbon actuating mechanism. The totalizer assemblage is contained between side plates 58 and 59, Fig. 3, which are supported from lugs 60, 30 61, 62 and 63 integral with the casting 52.

The platen is supported on a casting 64, which is attached to the casting 57 by screws 65 and 66. The platen casting 64 also provides a support for the escapement advancing mechanism for the platen.

It has been my aim in constructing this machine to make these different units of a structure that can be readily assembled and tested without reference to any of the other 50 portions of the mechanism and then the separate units assembled into the complete machine as will appear hereinafter. The connections between the separate units are comparatively few and each of said units is 55 capable of adjustment to perform its function independently of the action of any other of the units constituting my improved machine.

60 The totalizer.

The totalizer is supported on the lugs 60, 61, 62 and 63 on the front face of the casting 52 and the totalizer mechanism thereof is supported between two side plates 58 65 and 59. Rigidly mounted between said

plates is a shaft 105 (Fig. 11) on which is rotatably mounted a series of carrying wheels 106, one for each decimal place of the totalizer. Each of the carrying wheels 106 has three planes; 1st: that of a set of gear teeth 107; 2nd: that of a carrying tooth 108 and 3rd: that of a locking disk 109. A passing hollow or scallop 100 is in the locking disk and serves to lock a transfer gear 111 which serves to transfer the tens 75 from the totalizer gear 106 to the similar gear in the next higher decimal place. The transfer gears 111 of which there is one for each carrying wheel 106, are rotatably mounted upon a series of swinging arms 112 80 and 113, said arms being rotatably mounted on shafts 114 and 115 held between the totalizer side plates 58 and 59. Springs 116 and 117 serve to maintain the arms 112 and 113 in contact with a series of adjusting screws 85 118 which are mounted in a bar 119 supported between side plates 58 and 59.

The transfer gears 111 contain three planes. 1st: a plane of a gear 120 adapted to be acted upon by the carrying teeth 108, 90 which teeth it will be noted are spaced ten teeth apart upon the carrying gears 106, the scallops 110 in the locking disk 109 being located opposite said teeth. The second plane of the transfer gear 111 consists of a 95 star wheel 121 which co-operates with the locking disk 109 and the presence of the passing scallop 100 in said disk permits the star wheel to turn during the time the carrying tooth 108 is acting on the gear 120. 100 The third plane of the transfer gear 111 contains a gear 122 which meshes in the teeth 107 on the transfer gear 106 of next highest order. This arrangement constitutes the well known Geneva gear transfer chain and 105 by this means every tenth tooth rotation of the carrying gear 106 of lower order results in a one tooth rotation of the carrying gear of next higher order. It is well known that the Geneva chain just described is always 110 locked and it, therefore, becomes necessary to provide some means of inserting numbers in the intermediate wheels of said chain.

This is accomplished by the expedient of mounting the transfer gears 111 upon the 115 swinging arms 112 and 113 and, by mechanism hereinafter to be described, lifting the transfer gear connecting the carrying wheel 106 with the wheel 106 or next lower order bodily out of mesh with said gears 106 just prior to the rotation of the carrying gear 106 of higher order when the same is engaged by the master wheel. As soon as this rotation has been completed the swinging arm 112 or 113 as the case may be, is 120 restored to its normal position and the chain of gears 106 is again locked. It is to be noted that the gears 111 are placed in two angular positions relative to the carrying gears 106. This is for the purpose of al- 125 130

lowing space for the supporting arms 112 and 113. The two sets of transfer gears viz. those mounted on the arms 112 and 113 are just alike but by the expedient of mounting them in staggered arrangement throughout the length of the totalizer, space is obtained for the supporting swinging arms 112 and 113. When the transfer gears are lifted to allow the associated carrying wheels 106 to turn, the rectangular slots in the star wheel 121 are locked on bars 123 or 124, said bars being supported in the totalizer side plates 58 and 59.

In order to prevent any of the swinging arms 112 or 113 from being displaced from their normal position during the insertion of a number I have provided a safety bar 125 which is mounted on a shaft 126 turning in the side plates 58 and 59. This safety bar extends across all the swinging arms 112 and 113 and is provided with an operating face 127 which is adapted to be operated by a nose 128 on each one of the swinging arms 112 and 113. All of these arms are provided with a locking surface 130 and the safety bar is provided with a coöperating locking surface 129. It will be seen that upon any of the swinging arms being operated to raise its thereupon mounted transfer gear 111 from in mesh with its engaged carrying gears 106, that the safety bar 125 will be rotated and the locking surface 130 moving in the path of the locking surface 129 on the swinging arms 112 and 113 will serve to maintain all of said swinging arms except the one displaced, in their normal position. This being true, it follows that no matter how violently the carrying gears 106 are rotated that the transfer gears 111 must be held in mesh with said gears 106 and the carrying operation accordingly performed.

Meshing with the teeth 107 of the wheels 106 is a series of idlers 131 which are mounted on a shaft 132 mounted in the side plates 58 and 59. Each of these idlers meshes with a gear 133 which is rigid with a number bearing wheel 134 and is rotatably mounted on a shaft 135 between the totalizer side plates 58 and 59. Numbers on the disk 134 are visible through a window 136 provided in the totalizer cover 137.

The actuating mechanism.

The actuating mechanism is supported between the side plates 53 and 54 which in turn are supported between the side plates 50 and 51.

Numbers are inserted into the totalizer by means of a master wheel 140 which is slidably mounted on a shaft 141, said shaft having a squared section 142 which engages a square hole in the master wheel 140. In general the motion of the actuating mechanism may be described as follows:

65 A set of numeral keys are provided each

of which serves to rotate a peculiar shaped cam which I shall hereinafter term a goose-neck. Each of these cams engages a roller supported from a shaft and thereby rotates said shaft a differential amount. Mounted 70 on said shaft is a sector which is adapted to engage either a wheel rigid with the shaft 141 or a gear in mesh therewith. The sector is mounted so as to swing transversely and its position is controlled by a sliding plate 75 on the down stroke of the key. The sliding plate first throws the sector into mesh with either of the gears adapted to mesh therewith, then rotates the sector a differential amount and then withdraws the sector from mesh with either of said gears. This results 80 in the rotation of the shaft a differential amount and the direction of rotation of said shaft is determined by the particular one of the gear engaged by said sector. There are a number of dogging and alining operations 85 connected with the operation of the key which will be described at the proper time.

I shall now describe the mechanism by which the depression of the number keys is 90 translated into the appropriate rotation of the master wheel. Pivoted on a rod 145 supported between the side plates 50 and 51, is a series of key levers 150 to 159. On each of these levers is mounted a key 160 to 169. 95 These keys are of two different species having shanks which are thrown alternately to the right and left of the point 65 at which said keys 160 to 169 are pivoted upon the bars 150 to 159. On each of the bars 150 to 159 is an ear 144 which engages in a single key mechanism hereinafter to be described, and a projection 146 having a slot 147 in the upper portion thereof. This slot is adapted to engage with a pin 148 having a head 149, 105 said pin being riveted in the goose neck cams 170 which are rotatably mounted on the rod 143 supported in the actuator side plates 53 and 54.

It is to be understood that there is one of 110 these goose neck cams for each of the keys 150 to 159. The goose neck cam has an actuating face 171, Fig. 11, which is adapted to engage with one of a series of pins 172 which are supported by arms 173 from a 115 sector shaft 174. The goose neck cams are provided with a concentric slot which serves to prevent the pins 172 from overthrowing when the goose neck is brought into engagement therewith. The pins 172 are set in 120 spiral arrangement on the sector shaft 174 and each one of said pins is long enough to engage either of two successive goose neck cams 170. It will be observed in Fig. 6 that the goose neck cams are of two species alternately arranged. The odd numbered cams that is, the cams for the keys 1, 3, 5, 7 and 9 having their concentric surfaces farther from the cam shaft 143 on which said cams are rotatably mounted. This arrangement 130

is for the purpose of reducing the number of the pins 172. The goose neck cam 170 attached to the zero key has its concentric slot 175 so placed that when it engages the 5 pin 172 it will not rotate the sector shaft 174. The next goose neck cam 170 which is attached to the one key has its concentric slot arranged so that when it engages with the first pin 172 that the sector shaft 174 10 will be rotated the space of one unit. This arrangement of alternate goose neck cams is continued through the entire series.

The sector shaft 174 is held in its normal position by a spring 66 (Fig. 11) which extends between a pin 67 in said shaft and a stud 68 on the frame work. An arm 69 is rigid with the sector shaft and by its contact with the tie rod 70 which serves as one of the rods holding the actuator 15 20 plates 53 and 54 together, determines a normal position for the sector shaft 174.

When a key 160—169 is first depressed and before the sector shaft 174 is rotated there are certain universal operations 25 which occur. The first one of these to be described is the operation of a universal rock shaft 177 pivoted between the plates 53 and 54 which has mounted on it, a pair of arms 178 which serve to support a rod 30 35 179 which extends in the path of the heels 180 which are formed integral with each one of the goose neck cams 170.

During the first part of the key motion and before the goose neck cam 170 contacts 35 with any of the rollers 172 the heel 180 rotates the rock shaft 177 by means of contact with the rod 179. The heel 180 has a surface 181 which is concentric with the shaft 176 and the rod 179 is resting on said 40 45 surface before the goose necks start to turn the sector shaft 174.

The rock shaft 177 is held in its normal position by a pair of scissors 78 and 79 (Fig. 17), these being pivoted by stud 45 50 55 screws 80 and 81 to the frame work. A spring 82 serves to maintain the arms 78 and 79 in contact with a banking post 83 mounted in the frame work. In between the arms 78 and 79 is a pin 84 which is 60 65 70 mounted on an arm 85 rigid to the rock shaft 177. The motion of this rock shaft is as follows: It is first rotated in a counter clockwise direction (Fig. 17) against the spring pressed arm 79 during the contact 75 80 85 of the heel 180 with the rod 179 which then rests on the concentric portion of the heel 180 during the remainder of the down stroke of the key and finally escapes from the back side of the heel 180. Just before the 90 95 100 numeral key reaches the bottom of its stroke the rock shaft is then immediately returned to its normal position as shown in Fig. 17 which of course, returns the master dog 209, the auxiliary alining pawl 210 and the 105 110 115 master pawl 224 to their normal positions.

On the upstroke of the key the rock shaft 177 is rotated in the reverse direction against the scissor arm 78 and this serves to restore the sliding plate 185 and its connected sector 182 to their normal positions. Upon 70 75 80 85 90 95 100 105 110 115 120 125 130

This preliminary motion of the rock shaft 177 on the down stroke of the numeral key is used to perform several universal operations, 1st: to shift the sector into mesh with either the direct or reverse gear in a manner hereinafter to be described; 2nd: to rotate 80 a master dog which serves to unlock the chain of gears 106 and 111 in the totalizer; 3rd: to release the master pawl which normally holds the master wheel from turning; 4th: to release an auxiliary alining 85 pawl which serves to bring the totalizer gears into their proper position and 5th: to lock the master wheel from lateral shifting relative to the totalizer. I will now describe these operations.

On the sector shaft 174 (Fig. 17) is mounted a sector 182 which is pivoted on a rod 183 in a block 184 rigidly mounted on said shaft 174. The sector 182 may be thus transversely tilted with respect to the 95 sector shaft 174. The position of the sector is governed by a plate 185 which is slidably mounted in the frame work and has a slot 186 (Fig. 3) in the upper edge thereof and a second slot 187 in the lower edge. Engaging the slot 187 is a helical cam 188 which, as it will be seen by referring to Fig. 3, has its ends twisted so that when said cam is slightly rotated, it will bring the sector 182 from its tilted position as 100 shown in Fig. 3, into a position at right angles to the sector shaft 174. When in this position, the sector will engage either a direct gear 189 or a reverse gear 190 according to the position of a reversing handle hereinafter to be described. When the sector engages the gear 189, the master wheel 140 will be rotated in a direction to produce addition and when the sector 182 engages the reverse gear 190 said master wheel will be 105 110 115 120 125 130 rotated in a direction to produce subtraction. I shall describe the means for controlling the position of these gears hereinafter.

The helical cam 188 is mounted on a 120 shaft 191 pivoted in the frame work and has therein a slot 192 (Fig. 17) in which engages a pin 193 mounted on an arm 194 rigid on the rock shaft 177; consequently when said shaft is turned in a counter clockwise direction (Fig. 17), the helical cam 188 will be turned in a clockwise direction and the sliding plate 185 will move the sector 182 in a position at right angles to the sector shaft 174. When the sector is in 125 130

this position, it is in engagement with either the direct gear or reverse gear 190. Differential rotation of the sector shaft 174 which occurs as a result of the engagement 5 of the goose neck cams 170 with one of the pins 172 will then result in rotation of the gears 189 and 190 and consequent rotation of the master wheel 140.

The helical cam 188 has on it a pin 195 10 which is adapted to engage a cam surface 196 in a plate 197 which is mounted on a rock shaft 198 rotatably mounted in the frame work. Said plate has in it a slot 199 which engages a roller 200 mounted in an 15 arm 201 rigidly attached to a shaft 202. Referring to the slot 199 it will be seen that said slot has a hump 203 and a surface 204 concentric with the shaft 198. The preliminary motion of the rock shaft 177 will therefore, first rotate the shaft 202 in a clockwise direction (Fig. 17) and then further motion 20 of said rock shaft 177 will leave the shaft 202 in its displaced position without further rotation.

25 I shall now describe the operation of the auxiliary alining pawl and the master dog. Reference to Figs. 2, 11 and 20 will disclose that mounted between the side plates 53 and 54 are the rods 207 and 208 and slidably 30 mounted on said rods is a carriage 211 which serves to shift the master wheel 140 and a master dog 209 and an auxiliary alining pawl 210. Neglecting for a moment the mechanism by which this carriage 211 is 35 shifted, I wish to point out that said carriage has mounted in it a pair of plates 212 and 213, said plates being so arranged as to form a slot 214 between them, said slot embracing the master wheel 140 and serving to 40 shift said wheel on the shaft 141.

The carriage 211 has a side plate 215 on which is mounted the auxiliary alining pawl 210, said pawl being slidably mounted on a stud 216 and being held in its normal position by a spring 217 extending between a 45 stud 218 in the auxiliary pawl 210 and the frame work of the sliding carriage 211. The lower portion of the pawl 210 has in it a pin 219 which is pivoted in an arm 220 rigidly 50 mounted to the master dog 209. Obviously, a rotation of the master dog 209 in a clockwise direction (Fig. 11) will result in the withdrawing of the auxiliary pawl 210 from the totalizer carrying wheels 106. The master dog 209 is thus rotated by means of a 55 fork 221 in its lower arm embracing a rod 222 which is supported by hangers 223 from the shaft 202 previously described.

Another universal motion which occurs on 60 the first part of the down stroke of the numeral key is the action of the master pawl 224 (Fig. 18). Reference thereto will disclose that the shaft 177 has on it an arm 71 having a pin 72 therein, which pin is adapted 65 to contact with the cam surface 73 in the

master pawl 224. Said pawl is mounted on a shaft 74 rotatably mounted in the frame work and has a nose 75 which is adapted to enter and aline the teeth of the direct gear 189. A spring 76 extending between the 70 pawl 224 and a stud 77 in the frame work tends to maintain the pawl 224 in the teeth of the direct gear 189 and thereby aline said gear.

To recapitulate the universal motions 75 which occur on the first part of the down stroke of the key and before the goose neck cam 170 has contacted with any of the pins 172 on the sector shaft, it will be recalled that during said preliminary motion of the 80 key the master dog 209 is rotated in a clockwise direction (Fig. 11) and thereby lifting one of the swinging arms 112 or 113 of the totalizer. This results, as previously mentioned, in withdrawing the appropriate 85 transfer gear 111 from mesh with the totalizer gear 106 in engagement with the master wheel 140 and the totalizer gear 106 of next lower order. The auxiliary alining pawl 210 is withdrawn from the totalizer gear 106 of 90 higher order and the master pawl 224 is withdrawn from its engagement with the direct gear 189. This leaves the totalizer gears free to rotate. Further depression of the 95 numeral key results in rotation of the sector shaft 174 and said shaft is rotated a number of steps depending upon the particular key which has been depressed.

Full stroke mechanism.

100

I will now describe the mechanism which compels a complete up and down stroke of any of the numeral keys when once a key stroke has been initiated.

Each one of the goose neck cams 170 has 105 on it two series of teeth 225 and 226 and with said teeth are engaged the full stroke pawls 227 and 228, these pawls being rotatably mounted in the frame work and being held together by spring 229, which extends between them (Fig. 6). The front full stroke pawl 227 has on it an arm 230 which is adapted to engage an arm rigid to the rock shaft 177. The back full stroke pawl has mounted on it a similar arm 232. 110

115 It will be remembered that during the first part of the downward motion of the key, the rock shaft 177 is rotated in a counter clockwise direction (Fig. 6). This will withdraw the back full stroke pawl 228 from the path of the teeth 226. When the key has completed its back stroke the rod 179 will escape off of the heel 180 and during the up stroke of the key the rock shaft 177 will be rotated in the contrary or clockwise 120 direction. This will result in the withdrawing of the front full stroke pawl 227 from the path of the teeth 225. Each one of the 125 goose neck cams 170 is provided with sets of teeth 225 and 226 and thereby a complete 130

up and down stroke of the key is compelled when once the key is disturbed from its normal position.

5 *Means for shifting the platen and master wheel.*

I will now describe the means by which the carriage 211 is shifted step by step as the keys are depressed and, since the two 10 are linked together, the platen carriage 233 is shifted. Each one of the numeral key bars 150—159 has extending upwardly from it, a lever 234 (Fig. 6) which is adapted to operate a universal rod 235 which is 15 suspended by arms 236 from a shaft 237 rotatably mounted in the plates 50 and 51. Extending from the shaft 237 is an arm 238 (Fig. 1) to which on a stud screw 239 is pivoted a link 240 which is pivoted on 20 a stud screw 241 to a downward depending arm 242 rigid on a shaft 243 rotatably mounted in the plates 50 and 51. Extending from said shaft and rigid with the arm 242 is an arm 244 pivoted to which by a 25 stud screw 245 is an upwardly extending link 246 which is connected to the platen feeding mechanism hereinafter to be described. The link 246 will be reciprocated at each stroke of a numeral key.

30 A platen carriage 233 (Figs. 1 and 15) is slidably mounted on the balls 248 on ways 249 integral with the casting 64. This carriage has attached to its lower side a rack 250, Fig. 6, having teeth 251 thereon 35 which normally engage a gear 252 rotatably mounted on a stud 253 in a pair of escapement plates 254 (Figs. 15 and 16) rotatably mounted on a rod 255 rigid in the frame work. One of the escapement plates 254 40 on which is mounted the gear 252 has in it a cam slot 256 engaging in which is a pin 257 on the end of a bell crank 258 rotatably mounted on a stud 259 in the frame work.

Neglecting for a moment the operation of 45 the bell crank 258, I wish to call attention to the fact that when said bell crank is in its position, shown in Fig. 15, the pin 257 is in a locking portion of the slot 256 with the result that the escapement plates 254 50 will be rigidly held in its position shown in said figure and the gear 252 will be in engagement with the teeth 251 of the rack 250 which, as before noted, is rigid with the platen carriage. Obviously step by step 55 rotation of the gear 252 will result in the step by step feeding of the platen carriage 233.

I shall now describe the mechanism which transforms the up and down motion of the link 246, which motion it will be remembered occurs once on the depression of each of the numeral keys, into a step by step rotation of the gear 252 and thereby results in a feeding of the platen carriage 233 one step 65 for each depression of a numeral key.

Rotatably mounted on the rod 255 is a plate 260 which is held in a normal position by a spring 261 extending between a stud 262 in said plate and a stud 263 in the escapement plate 254. The link 246 is pivoted on the plate 260 by the stud screw 264. Up and down motion of the link 246 will therefore, result in the oscillating of the plate 260 about the rod 255. Pivoted on said plate by stud 265 is a link 266 which is pivoted at 267 on a rocker 268, which is rotatably mounted on the stud 253 serving to carry the gear 252. Rigid with said gear is a ratchet wheel 269 and in engagement with the teeth of said wheel is a feeding pawl 270 pivoted on the rocker plate 268 at 271. A spring 272 serves to hold the pawl 270 into engagement with the teeth of the ratchet wheel 269.

A retaining pawl 273 pivoted on a stud 276 on the escapement plates 254 and held in contact with said wheel by a spring 275 serves to prevent backward rotation of the ratchet wheel 269 when the same is being fed by the pawl 270. Obviously reciprocation of the link 246 will result in the rocking of the plate 260 about the rod 255 and this by means of the connecting link 266 will result in oscillation of the rocker 268. The pawl 270 will thereupon be drawn backward a space of one tooth and by motion of the link 246 which corresponds to the return motion of any of the numeral keys, the ratchet wheel will be fed one step and the rigidly attached gear 252 will be fed one step also thereby advancing the platen carriage 233. A stud 277 in the escapement plate 254 serves to limit the forward motion of the feeding pawl 270 jamming said pawl between the stud and the ratchet wheel 269. Thus, when the rocker 271 is in its normal position, the ratchet wheel and its then connected platen carriage 233 is rigidly locked against either forward or backward motion.

The object of mounting the gear and these feeding parts on an escapement plate 254 instead of mounting them rigidly in the frame work of the machine, is to permit the disengagement of the gear 252 from the rack 250 when it is desired to tabulate the carriage as will be hereinafter described. This disengagement is accomplished by rotation of the bell crank 258 about its pivot 259, the shape of the slot 256 being such that on rotation of the bell crank 258 (Fig. 15) in a clock wise direction, the escapement plate 254 will be lowered and the gear 252 withdrawn from engagement of the rack teeth 251. The platen carriage 233 is then free to 120 be located in any desired position.

The tabulating mechanism.

I shall now describe the mechanism by means of which the platen carriage 233 is 130

tabulated to its proper position, prior to the insertion of a number by means of the numeral keys, as before described. It is noted that the feeding of the platen carriage 233 is of the force feed type, that is, the platen is fed during the up stroke of the numeral keys. Obviously if one were to withdraw the gear 252 from the rack 250, the platen carriage 233 would be perfectly free to be moved in either direction and my tabulator mechanism has for its object to first withdraw the gear 252 from engagement with the rack 250 thereby freeing the platen carriage 233 and then to positively locate said carriage in a position dependent upon the particular tabulating key which has been operated.

The tabulating mechanism can probably be best understood from an inspection of the perspective view thereof shown in Fig. 20, in which is shown two tabulating keys and the mechanism by which these keys locate the platen carriage. I have provided a set of eight tabulating keys which I will number 280. These keys correspond to the different decimal orders of the digits of the numbers which are put into the machine. The keys 280 are pivotally mounted at 281 on the tabulator bars 282 which are rotatably mounted on the rod 145 which is mounted between side plates 50 and 51 and also serves as the fulcrum for the numeral keys 150—159. The keys 280 are mounted on stems 284 which are guided through slots in the cover plate 285 fastened on the frame work of the machine. Each one of the tabulator bars 282 has at its rear end a slot 286 which engages a pin 287 in a rear tabulating cam 288 which is rotatably mounted on a rod 289 rigid in the side plates 50 and 51.

40 The rear cam 288 has an arm 290, having a ball 291 thereon which engages in a fork 292 in an associated front tabulating cam 293, said cam being rotatably mounted on a rod 294 rigid on the frame work of the machine. The front tabulating cam 293 has a jaw 295 similar to a jaw 296 on the rear tabulating cam 288 and when the associated tabulator bar 282 is depressed, the jaws 295 and 296 will close on a rod 297 rotatably mounted in the frame work of the machine. (Fig. 22). The jaws 295 and 296 have a radial portion 298 and 299 which is adapted to contact with the rod 297 and also a locating portion 300 and 301 which is adapted to locate a pin 302 supported between arms 303 and 304 rigidly mounted on the shaft 297. It is evident that depression of the tabulator bar 282 will result in the locating of the shaft 297 in a position dependent on the position of the arms 303 and 304 relative to said shaft. The successive pins 302 are located on the shaft 297 in spiral arrangement and each one of the tabulator bars 282 has associated with it a back tabulating cam 288 and a front tabulating cam 293. Depression of any of the

tabulating keys 280 will therefore, locate the rod 297 in a predetermined position.

Rigidly attached to the rod 297 is an arm 305 serving to support a stud screw 306 pivoted on which is a twisted link 307 which is pivoted on a stud 308 in a bell crank lever 309 pivoted at 310 to the frame work of the machine. Said bell crank lever has mounted in its upper end a pin 311 which engages a slot 312 in an ear 313 on a plate 314 rigid with the platen carriage 233.

Each one of the rear tabulating cams 288 has on it a heel 315 which is adapted to contact with and operate a universal rod 316; said rod being attached to a rock shaft 317 by arms 318. Displacement of the rod 316, will therefore, rotate the rock shaft 317. As before noted the first motion of any of the tabulating keys serves to disengage the gear 252 from the platen carriage 233 and this is accomplished by providing on the rod 317, an arm 319 (Fig. 1) having a stud 320 on which is pivoted a twisted link 321 which is connected to a stud 322, Fig. 15, on the bell crank 258.

The first portion of the stroke of the tabulating key serves to shift the rod 316 after which said rod rides on the concentric surface of the heel 315. Therefore, during the first part of the tabulator key stroke, the platen carriage is disengaged from its driving mechanism thus leaving it free to be located in a position determined by the contact of the surfaces 300 and 301 of the front and rear tabulating cams 293 and 288 with a roller 302.

The action of the tabulator keys has also another function, that is, viz. the platen is line spaced each time a tabulator key is operated. This is accomplished by providing an arm 323 rigid with the rock shaft 317, (Fig. 20) said arm carrying a pin 324 which engages a slot 325 in a lever 326 rigid on a rock shaft 327 rotatably mounted in the frame work of the machine. A rod 328 is supported on the rock shaft 327 between arms 329 and engaging the rod 328 is a link 330, which is guided by a slot 331 in a plate 332 rigid in the platen carriage 233 and this upwardly extending end is pivoted on a stud 333 which carries a feeding pawl 334 and is mounted on an arm 335 rotatably mounted on the shaft 336 which carries the platen 337. Rigid with the platen is a ratchet wheel 338. The pawl 334 is held in engagement therewith by a spring 339. The pawl 334 is normally out of contact with the ratchet wheel 338 and on the down stroke of the tabulator key is drawn into contact with said wheel and then continued motion of the pawl feeds said wheel a space of one tooth. The ratchet wheel 338 is prevented from rotating except when a force is applied thereto by a roller 340 mounted on a stud 341 on an arm 342 pivoted to the platen carriage 130

at 343 and held by a spring 344 extending between said arm and a stud mounted on the platen carriage. When the tabulator keys are not depressed the platen 337 may be turned in either direction, the roller 340 permitting such a movement and serve to locate the platen by means of the ratchet wheel 338. However, the depression of a tabulator key 280 results in bringing the pawl 334 into engagement with said wheel and the consequent feeding of the platen one space.

Upon the up stroke of the tabulator key 280, a spring 345, Fig. 4, extending from a stud 346 in the frame work and an arm 347 attached to the rock shaft 317 serves to return the said shaft to its normal position upon the up stroke of the tabulator key. This serves to return the escapement plate 254 to its normal position and thereupon re-engage the platen carriage 247.

I shall now trace out the connection between the platen carriage 247 and the carriage 211 controlling the position of the master wheel 140. Attached to the platen carriage 233 is a stud screw 348 (Fig. 20) to which is attached a twisted link 349 which engages a stud screw 350 in a bell crank 351 rotatably mounted on a stud 352 in the frame work. The bell crank 351 carries a stud screw 353, pivoted on which is a link 354 which is pivoted also onto a stud 355 mounted in a bell crank 356 mounted on a stud screw 357 which is mounted on the framing of the machine. The other end of the bell crank 356 has a stud screw 358 on which is a link 359 extending to a stud screw 360 mounted on an ear 361 which projects from the plate 215 of the carriage 211.

Step by step motion of the platen 337 as resulting from a depression of the keys is communicated to the carriage 211 which it will be observed progresses in the opposite direction from the platen 337. It will be also observed that in case the platen 337 is tabulated by means of any of the tabulating keys 280 that the carriage 211 will be simultaneously tabulated also.

50 The printing mechanism.

The printing mechanism consists of a set of type bars 362, one for each of the numeral keys. Each of these bars is pivoted at 363 in a bracket 364 to the casting 57. This mounting being similar to the mounting customarily used in typewriters. A segment 365 supported from the casting 57 by a pair of pillars 366 serves to determine the normal position of the type bars. The type bars are connected to the numeral keys by a mechanism which has for its object the prevention of any motion of said type bars until the number corresponding to the key has been entered into the totalizer. During the

entry of said number, power is being stored by the numeral key being operated and as soon as the number is entered into the totalizer the type bar is released and flies up striking the platen.

The object of this mechanism is to provide an efficient safeguard against entering one number into the totalizer and printing a different number.

I shall now describe the details of this printing mechanism. Each of the type bars has pivoted to it at 367 a link 368, the other end of which is pivoted on a stud screw 369 on the end of a lever 370 (Fig. 1). The levers 370 are pivoted on the rod 145 which serves as the common support for both the numeral and tabulator keys. The lever 370 is connected to its associated numeral key by a spring 371 extending from a hole 372 in the lever 370 to a stud 373, in the key lever 150. Rotatably mounted in the plates 50 and 51 is a rock shaft 374 on which are the arms 375 supporting the rod 376 and also the arms 377 which support a rod 378, the rod 376 extending in the path of all of the levers 370 and the rod 378 in the path of all the numeral key levers 150—159. Said key levers are provided with an upwardly extending cam 379 which is adapted to contact with the rod 378 when the key is depressed. When contact is established between the cam 379 and the rod 378 at a certain point in the depression of a numeral key the shaft 374 is rotated and the rod 376 is depressed and the lever 370 is permitted to escape whereupon the tension of the spring 371 operates the associated type bar which, by means of a type mounted thereon, prints a number on the platen. Each of the key levers 150—159 has attached to it a returning spring 380 extending from said keys to a bar 381 mounted in the frame work. The tabulator bars 282 are also provided with similar returning springs attached to the bar 381. The normal position of all the keys is determined by their contact with a universal stop 382 which is provided on its bottom surface with felt 383 or other sound deadening material. Each of the levers 370 has mounted in it a pin 384 which is adapted to contact with the rear portion of the cam 379 upon the return of the key and thus the return of the levers 370 and their connected type bars to their normal position is assured upon the return of the key.

To sum up: The operation of any of the numeral keys during the first part of the down stroke, performs certain universal operations connected with the calculating mechanism. During this period power is being stored up in the spring 371. Next the goose neck cams 170 make contact with the pins 172 and the proper number is thus rolled into the totalizer. As soon as the actuation of the totalizer is completed the rod 376

escapes from the top portion of the lever 370 and the type bar is then actuated by the power of a spring 371. On the back stroke of the key, the type bar is restored to its normal position, if it is not already rebounded to such a position, and the escapement is actuated thus feeding both the platen carriage 233 and the carriage 211.

10 *The gear reversing device.*

This part of the mechanism is used for two purposes. First to determine whether a number set up on the keys shall be entered into the machine, or not and if entered 15 whether the number shall be entered in addition or subtraction.

The gear reversing device, Figs. 2, 3, 17 and 21, is controlled by a lever 385 which extends from a plate 386 pivoted on a stud screw 387 mounted on the side plate 54 which supports the actuator assemblage. Rigid with the plate 386 is a second plate 389 which is attached to the plate 386 by means of a dowel pin 390 and has a slot 391 therein 25 (Figs. 1 and 21) which co-operates with a stud screw 392 mounted in the plate 54. The extent of motion of the lever 385 is thus determined. The plate 386 has on its under side three locating notches 393, 394 and 395. 30 Co-operating in these notches is a locating pin 396 which is mounted on a bell crank 397 pivoted on a stud screw 398 in the plate 54. A spring 399 extending between the bell crank 397 and a stud 400 on the plate 54 35 serves to maintain the pin 396 in contact with the locating notches 393, 394 and 395, thus locating the lever 385 in any of its three possible positions. The plate 389 has a right angle portion 401 on the edge thereof (Figs. 40 3, 7 and 21) and in this portion is a slot 402 which engages a pin 403 mounted on the gear shift rod 404 which is slidably mounted in the frame work, the pin 403 engages the slot 402 which thus serves to locate the gear 45 shift rod 404 in any of its three possible positions. The gear shift rod 404 has rotatably mounted upon it, the reverse gear 190, said gear being held between suitable collars so as to have no longitudinal motion relative 50 to the gear shift rod 404. On the end of the rod 404 is a pin 405 which engages one end of a reversing lever 406 pivoted in the frame work at 407. The other end of said lever engaging in an annular slot 408 in the shaft 55 141. Motion of the gear shift rod 404 will thus produce motion of the shaft 141 in the opposite direction and since the direct gear 189 is rigidly mounted to said shaft, said gear will be shifted also. It will be remembered that the gears 190 and 189 are the ones which are engaged by the sector 182 when the sector shaft 174 is rotated. According 60 to the position of the gears 190 and 189 one or the other of them will be engaged by the

sector and consequently the shaft 141 and the master wheel 140 turning therewith will be rotated either in a direct or reverse direction. When the reversing handle 385 is in its middle position, the gears 190 and 189 are in line with each other and neither of them are engaged by the sector when the numeral key is depressed. This corresponds to a number being listed but not entered into the totalizer.

The ribbon movement is connected with 75 the handle 385 to the end of shifting the ribbon so that the type will print in red when the machine is operating in subtraction. However, this particular mechanism will be described in connection with the description 80 of the ribbon movement.

The ribbon movement.

The ribbon is wound on one or the other of two spools 409 and 410 which are rotatably mounted on studs 411 and 412 mounted on the lugs 55 and 56 of the casting 52. The ribbon is led from the spool 409 through a guide 413 and from thence through the ribbon vibrator plate 414 which is reciprocatingly mounted on the frame work through the ribbon guide 415 and from thence to the spool 410. The spools are provided with mechanism to advance the ribbon upon each stroke of a type bar and also with mechanism to reverse the direction of winding when the ribbon on either spool shall have become unwound. The vibrator plate 414 is also provided with mechanism to raise it and the threaded ribbon in the path of the type before said type strike upon the platen. Considering the vibrating mechanism first, reference to Fig. 21 will disclose that the rock shaft 237, which it will be remembered, was vibrated upon each stroke of the numeral key has rigid with it, an arm 416 having a stud screw 417 mounted thereon. Extending from said stud screw is a link 418, the other end of which is pivoted on a stud screw 419 mounted on a bell crank 420 mounted on a stud screw 421 in the frame work of the machine. The bell crank 420 will thus be turned in a counter clock wise direction (Fig. 1) upon each stroke of the numeral key. Extending from a stud screw 422 on the bell crank 420 is a twisted link 423. This connects to a stud screw 424 which serves to vibrate a lever 425 on which the screw 424 is mounted. The lever 425 has its fulcrum about a pin 426 which is mounted in a bell crank 427 pivoted on a stud 428 on the frame work and connected by a link 429 to a bell crank 430 which is mounted on the stud screw 421 which serves as the fulcrum for the bell crank 420.

The bell crank 430 carries a stud 431 pivoted to which is a link 432 which is pivoted to a lever 433 which is pivoted on the stud

screw 398 which serves as a pivot for the bell crank 391. A pin 434 is mounted in the lever 433 and engages a slot 435 in the plate 386. This slot 435 has two portions, one 5 436, Fig. 1, which is concentric with the center 387 about which said plate rotates and the other 437 serves to rotate the lever 433 in a counter clock wise direction. Said rotation will serve to shift the fulcrum 426 of the lever 425 in a counter clock wise direction also (Fig. 21) and consequently when 10 the lever 425 is oscillated upon each stroke of the key, the end 438 of said lever which is pivoted on a stud screw 439 will be raised 15 higher on each stroke of the key than when the fulcrum 426 is in the position shown in Fig. 21. The stud screw 439 is mounted in the ribbon vibrator plate 414 which is reciprocatingly mounted on the frame work 20 by means of two stud screws 440 and 441 which engage slots in said plate. Since the lever 425 is oscillated on each stroke of the key, it is obvious that the ribbon 442 will be brought in the path of the type and therefore, 25 said type will print upon the platen. The ribbon 442 has on its under portion 443 a strip of different color than from the color of the upper portion and therefore, when the fulcrum 426 of the lever 425 has been 30 shifted as a result of throwing the lever 385 to its subtraction position numbers will be printed on the platen in this characteristic color. It is to be noted that on account of the concentric portion 436, that numbers 35 which are printed but not calculated will be printed in the same color as the numbers which are added.

The ribbon spools are fed step by step upon the actuation of each type bar by an 40 arm 444 which is rigidly mounted on the shaft 237 (Fig. 6) which it will be remembered is rocked for each stroke of the numeral key.

The arm 444 has mounted in it a pin 445 45 which engages a slot 446 in a lever 447 pivoted on a shaft 448 rotatably mounted in the frame work. Said shaft has mounted on it a ratchet wheel 449 which is fed by a pawl 450 mounted on the lever 447. Rigidly 50 attached to the ratchet wheel 449 is a gear 451 which engages a gear 452 rigid on a shaft 453 (Fig. 2) which shaft is rotatably and also slidably mounted in the frame work. On either end of the shaft 453 is a 55 pair of beveled gears 454 and 455, each of which is adapted to mesh with corresponding bevels 456 and 457 mounted on the ribbon spools 410 and 409. The particular pair of bevels which will be in engagement 60 is controlled by a cam 458 rigid on the shaft 453 and held in either one position or the other by a snapper spring 459 mounted in the frame work. Pivoted on the frame work are a pair of ribbon shifters 65 460 and 461 which by means of a spring

462 connecting them are held in contact with the unwound ribbon on the spools 409 and 410. The hub of the bevel gears 454 and 455 have mounted in them the shifter pins 463 and 464 and these pins are adapted 70 to come in contact with incline faces 465 and 466 on the ribbon shifters 460 and 461, when the ribbon on either of the spools has been unwound sufficiently for either of the said pins to come into the path of the cam, 75 further rotation of the shaft 453 will result in forcing the cam 457 against the spring 458 until said spring has passed over the hump of the cam. Then the shaft 453 will be thrown the balance of its travel by the 80 action of said spring and the rotation of the spools reversed and the ribbon accordingly fed in the reverse direction.

It is to be noted that the gear 451 (Fig. 2) has a wide face which permits the shaft 453 85 to be shifted and to still allow the gear 452 to remain in mesh with its driving gear 451.

Mounting for the paper roll.

My machine is designed to print numbers 90 upon a strip of paper which may be conveniently supplied in a roll (Fig. 19) and I have provided a bracket 467 which is attached to the rear part of the machine as a mounting for this roll. Instead of moving 95 the paper roll with the platen carriage 233, I have provided a paper guide 468 which has its edges 469 and 470 turned down to form an accurate guide for the paper and has its lower edge 471 formed in the arc of 100 a circle to allow the paper to bend as the platen carriage 233 is reciprocated. This arrangement is of marked advantage since it obviates the necessity of shifting the heavy paper roll on the one hand or the type 105 basket on the other hand.

The platen carriage 233, Fig. 9, is built up on a casting 472 the lower side of which contains the ball raceway 473, Fig. 1, and also serves to support the side plates 474 and 475 110 between which the platen roll 337 is pivoted. A knurled thumb nut 476 is provided rigid on the shaft 336 for the purpose of feeding the platen manually to any desired point. The side plates 474 and 475 are connected by a rod 477 which slides in a channel 478 in an arm 479 which extends upwardly from the casting 64 in which the underside of the ball race is cut. The platen carriage 233 is thus supported at three 115 points, two of them being the balls 248 and the third point is the rod 477. A ball retainer 481, Fig. 5, is provided and the edge of this retainer has on it a rack 482 which engages with a gear 483 rigidly fastened 120 to a gear 484 of double the diameter and rotatably mounted on the stud screw 485 fastened to the frame work. The gear 484 engages in a rack 486 rigid to the platen carriage 233. The balls are thus maintained 125 130

in their proper position permitting free motion of the platen carriage.

Single key mechanism.

5 This consists of a series of pendants 487 which are pivoted at 488 between plates 489 and 490 (Figs. 3 and 6). Both the tabulator keys and number keys have a projection 144 which passes between the elements 10 of the single key mechanism and the end pendants have pins 491 and 492 which engage in slots in the plate 489. It is, therefore, not possible to depress more than one key at a time and this remark applies to 15 the tabulator keys as well as the numeral keys. That is, it is not possible to depress a numeral key while a tabular key is depressed or vice versa. Neither is it possible to depress two tabulator keys or two numeral keys at the same time.

The master dog 209 is provided with a horizontal extending portion 498 which engages the teeth of a rack 499 which is rigid in the frame work. This serves to hold the 25 carriage which controls the motion of the master wheel immovable during the insertion of a number.

The tabulator keys are provided with a full stroke mechanism to prevent the return 30 of said keys before they have been completely depressed. Reference to (Fig. 20) will disclose that each of the rear tabulating cams 288 is provided with a set of teeth 500 coöperating with which is a universal-pawl 35 501, Fig 6, pivoted in the side plates 50 and 51 at 502. A spring 503 between the pawl 501 and the frame work serves to maintain said pawl in contact with the teeth 500. The position of the pawl 501 is controlled by an 40 arm 504 rigid with said pawl and controlled by a finger 505 rigid to a rock shaft 506, between side plates 50 and 51 and controlled by a universal rod 507 supported from said shaft by the arms 508 and extending in the 45 path of projections 509 on the cams 288. When the tabulator bars 282 are depressed the projection 509 rocks the shaft 506 in a counter clock wise position (Fig. 6) consequently allowing the pawl 501 to come into 50 engagement with the teeth 500.

The rod 507 is held in a normal position between a pair of scissor levers 510 and 511 which are pivoted on the plate 51 at 512 and held together by spring 513 which extends 55 between them. Upon the completion of the down stroke of the tabulator bar 282 the universal rod 507 escapes from the projection 509 and on the down stroke of the key the rock shaft 506 is rotated in a clock wise direction (Fig. 6). This withdraws the pawl 501 from the teeth 500 and the tabulator bar 282 is allowed to return to its normal position without interference from said pawl. The action of this full stroke mechanism for 60 65 the tabulator keys is quite similar to the

action of the full stroke mechanism, consisting of the pawls 227 and 228 for the numeral keys.

Many changes and modifications may be made in the precise mechanism herein disclosed by those skilled in the art without departing from the spirit of my invention, since I claim:—

1. In a calculating machine, the combination of a series of adding keys, a series of 75 actuators each controlled by one of said adding keys, a differential member operated directly by said actuating members, a universal bar controlled directly by each of said actuating members, and full stroke mechanism 80 comprising coöperating parts, one of which is carried directly by each of said actuating devices.

2. The combination with a differential member, a universal bar, one or more full 85 stroke pawls, and a set of numeral keys, of a set of actuating devices one operated by each key and each of said actuating devices having one part thereof acting directly on said differential member, another part thereof 90 acting directly on said universal bar, and another part thereof coöperating directly with said full stroke pawl or pawls.

3. The combination with a differential member, a universal bar, and one or more 95 full stroke pawls, of a series of actuating devices one operated by each key and each of said actuating devices having one part thereof acting directly on said differential member, another part thereof acting directly 100 on said universal bar, and another part thereof coöperating directly with said full stroke pawl or pawls, and a series of key levers each connected directly to one of said actuating devices.

4. The combination with a differential shaft having spirally arranged arms, a universal bar, one or more full stroke pawls, and a set of numeral keys, of a set of pivoted plate-like actuating members, each member comprising a cam acting on one of said spirally arranged arms, each member having a lug projecting from one edge thereof to engage said universal bar and each member having on its periphery ratchet teeth 110 for coöperation with said full stroke pawl or pawls.

5. In a calculating machine, the combination of a set of numeral keys, a set of tabulator keys, a set of projections on said numeral and tabulator keys, said projections being in alinement, a set of pendants, each of which is adapted to pass between any two of said projections, and means to constrain the motion of said pendants, whereby but a single one of said projections is permitted to be forced between said pendants at one time.

6. The combination of a computer carriage traveling transversely of the machine, a rock shaft parallel with the direction of 130

travel of said carriage, positive and constantly maintained connections between said carriage and said rock shaft whereby said shaft turns in unison with the travel of the carriage, a set of tabulator keys, and means operated thereby to rock said shaft in either direction, each key to a definite position peculiar to that key.

7. In a calculating machine, the combination with a carriage, of means for controlling the movement of the carriage in both directions comprising a series of keys, a rock shaft operatively connected to the carriage to move the same and provided with a series of spirally arranged arms, one arm corresponding to each key, and means operated by each of said keys to move the corresponding arm to a given position, said key operated means comprising two levers that are moved in opposite directions by the associate key and which engage a part of the arm between them at the termination of the stroke.

8. In a calculating machine, the combination with a carriage, of means for controlling the movement of the carriage in both directions comprising a series of keys, a rock shaft operatively connected to the carriage to move the same and provided with a series of spirally arranged arms, one arm corresponding to each key, means operated by each of said keys to move the corresponding arm to a given position, said key operated means comprising two levers that are moved in opposite directions by the associate key and which engage a part of the arm between them at the termination of the stroke, and full stroke mechanism for each of said keys.

40 9. In a calculating machine, the combination of a register, actuating means therefor comprising means for setting the mechanism for add, disconnect and subtract, said setting means comprising a device movable to three positions, a cam controlled by said device and having a dwell for the add and disconnect positions and an offset for the subtract position, printing mechanism including ribbon vibrator mechanism, and a follower controlled by said cam and controlling said ribbon vibrator mechanism so that when the mechanism is set for add and for disconnect the printing is in one color and when it is set for subtract the printing is in another color.

10. In a calculating machine, the combination of a movable platen, a set of tabulator keys adapted to tabulate said platen in either direction and thereby locate any position determined by the particular tabulator key operated, means to rotate said platen step by step, and means common to all of said tabulator keys to operate said rotating means upon the operation of any 65 of said tabulator keys whether said tabu-

lator sets said platen toward the right or toward the left.

11. In a calculating machine, the combination of a shaft having supporting members thereon, contact devices supported by said members in spiral arrangement, each member supporting a plurality of said contact devices, a numeral key, a cam connected to said numeral key and adapted to engage one of said spirally arranged contacts on the shaft and locate the latter in a position depending upon the numerical value of said key and the cam controlled thereby, a second numeral key of a different numerical value and connected with a cam differing from the first cam and operative on the same spirally arranged contact which is engaged by the key controlled cam of the first mentioned key.

12. The combination with a set of numeral keys, of a differential shaft having a series of arms projecting therefrom less in number than said numeral keys, a spirally arranged series of rollers or pins supported by said arms, certain of said arms supporting two pins, and cams operated by said keys, a plurality of said cams differing from one another and acting on one of said pins whereby the different keys impart different extents of rotation to said shaft, the difference being due partly to the spiral arrangement of the pins and partly to the difference in the cams.

13. In a calculating machine, the combination of a decimal carriage, means to advance said decimal carriage step by step, a movable platen attached to said decimal carriage by a linkage adapted to change the motion of the decimal carriage in one direction to a corresponding motion of the platen in the contrary direction, said decimal carriage and said platen always being connected to each other, and a set of tabulator keys operative on said decimal carriage and platen to locate both of them simultaneously in a position determined by the particular tabulator key which has been operated.

14. In a calculating machine, the combination of a set of numeral keys, a differential member having a series of graduated contacts less in number than said keys, a series of coöperating contacts, one for each key, said coöperating contacts being of two kinds, and two of them coöperating with a single one of the first mentioned graduated contacts, whereby the differential motion of said differential member is due partly to the graduation of its own contacts and partly to the difference between the different key controlled contacts.

15. In a calculating machine, the combination of a movable master group consisting of a master wheel and a universal member, a stationary rack attached to the framework

of the machine, a set of numeral keys, and means to definitely aline said master group by engagement of said universal member with said rack upon the operation of any of 5 said numeral keys.

16. In a calculating machine, the combination of a master wheel, means to advance the same step by step, a shaft having a section upon which said master wheel is non- 10 rotatably but slidably mounted, a gear upon said shaft, a second gear in mesh with said first gear, means connecting said gears, whereby said second gear is moved in one direction when said first gear and the at- 15 tached shaft is moved in the opposite direction, and a third gear adapted to engage either of said previously mentioned gears according to the position of said gears and thereby reverse the motion of said master 20 wheel.

17. In a calculating machine, the combination of a master wheel, a set of numeral keys, a vibrating sector, a shaft upon which said master wheel is slidably mounted, a 25 gear rigid to said shaft, a second gear in mesh therewith, means to shift said gears longitudinally with reference to each other, whereby it is determined that one gear or the other shall be engaged by said sector, 30 and means brought into operation upon the depression of any of said numeral keys to shift said sector laterally into mesh with one or the other of said gears and then rotate the same a differential amount and then 35 withdraw said sector from its engagement.

18. In a calculating machine, the combination of a carriage, feed mechanism therefor comprising a pawl, a wheel operated by said pawl, means for actuating said pawl to 40 feed the wheel and carriage and to lock the pawl and the parts controlled thereby at the end of their movement, tabulator mechanism, and means automatically controlled thereby for moving said wheel bodily 45 to free the carriage from control thereof without disturbing the relation of the pawl and before the carriage is moved under control of said tabulator mechanism.

19. In a calculating machine, the combination of a carriage, numeral keys, a pawl controlled by said numeral keys, a wheel controlled by said pawl and operative to control the feed movement of the carriage, means for locking the pawl and the wheel 50 controlled thereby at the last part of the movement of said pawl, a movable frame which carries said pawl and wheel, tabulator mechanism for controlling the movement of said carriage, and means under control of 55 said tabulator mechanism for moving said frame to free the carriage from control of said wheel before the tabulator mechanism operates to move the carriage.

20. In a calculating machine, the combination of a carriage, a feed rack connected

therewith, a gear wheel meshing with said feed rack, a ratchet wheel connected with said gear wheel, a driving pawl coöperating with said ratchet wheel, a pivoted frame by which said gear and ratchet wheels and said 70 pawl are carried, tabulator mechanism for controlling the movement of the carriage, and means controlled by said tabulator mechanism for effecting a pivotal movement of said frame to disengage said gear wheel 75 from the carriage rack without affecting the relation of said wheels and pawl.

21. In a calculating machine, the combination of a set of numeral keys, a differential mechanism operated thereby, a decimal 80 carriage to determine the decimal place of operation, a force feed escapement for said decimal carriage, a printing mechanism, a traveling platen connected to said decimal carriage and adapted to be fed in the reverse 85 direction from said decimal carriage, a set of tabulator keys, means to rotate said platen, and mechanism connecting said platen rotating means and said escapement with said tabulator keys, whereby said escapement is disabled during the tabulation 90 of said decimal carriage and the simultaneous rotation of said platen.

22. In a calculating machine, the combination of a decimal carriage, a set of tab- 95 ular keys, mechanism connecting said keys and said carriage whereby said carriage may be tabulated in either direction by the power applied to one of the said keys to a position determined by said key, and full-stroke 100 mechanism and single key mechanism operative on said tabulator keys to compel any operated key to be operated through the entire cycle before the operation of a second tabulator key is permitted.

23. In a calculating machine, the combination of a carriage, carriage feed mechanism, tabulator mechanism including a key, and automatic operating means for freeing the carriage from the control of the carriage feed mechanism on the operation of the tabulator key and for reestablishing an operative connection of the carriage with its carriage feed mechanism after the tabulating movement of the carriage has been 115 effected and before the beginning of the return movement of the tabulator key.

24. In a calculating machine, the combination of a carriage, carriage feed mechanism, tabulator mechanism including a tabulator 120 key and means for positively moving the carriage by an actuation of said key, and automatically operating means controlled by said tabulator mechanism for releasing the carriage from control of its feed mechanism 125 before the tabulator movement of the carriage takes place and for restoring the carriage to the control of said feed mechanism before the actuated tabulator key starts its return movement.

25. In a calculating machine, the combination of a carriage, carriage feed mechanism, tabulator mechanism including a tabulator key and means controlled thereby for moving the carriage in either direction depending on the position of the carriage when said key is actuated, and automatically operating means controlled by said tabulator mechanism for releasing the carriage from control of its feed mechanism before the tabulating movement of the carriage takes place and for restoring the carriage to the control of said feed mechanism before the actuated tabulator key starts its return movement.

26. In a calculating machine, the combination of a master wheel, means to advance the same step by step, a shaft having a section on which said master wheel is non-rotatably but slidably mounted, a gear upon said shaft, a second gear in mesh with said first gear, a lever pivoted in the framework connecting said second gear and said shaft, to the end that any lateral motion of said shaft is reproduced in oppositely-directed lateral motion of said second gear, and a third gear adapted to engage either of said previously mentioned gears according to the position of said gears and thereby reverse the motion of the master wheel.

27. In a calculating machine, the combination of a set of numeral keys, a differential mechanism, a platen, printing mechanism, an escapement for said platen, means connecting any of said numeral keys to said differential mechanism, printing mechanism and escapement mechanism, to the end that the stroke of the numeral key will first operate said differential mechanism while storing up power to operate said printing mechanism, then release said printing mechanism, permitting it to print upon said platen, a pawl operative on each of said numeral keys to prevent an incomplete stroke of said keys, whereby the differential mechanism might be operated without operating the printing mechanism, and means operative on the up stroke of said keys to feed said escapement.

28. In a calculating machine, the combination of a totalizer unit, a differential unit, a common framework to support said units, a printing unit including a platen mounted on a framework independent of said first framework, and a pair of side plates affording a common support for said two frameworks, whereby either of said frameworks may be disengaged from said side plates and the parts supported thereby adjusted without disturbing the adjustment of the mechanism on the other framework.

29. In a calculating machine, the combination of a totalizer unit, a differential mechanism unit, said units being supported on a common framework, a printing unit

supported on a framework independently of said first framework, tabulator mechanism operative on said printing unit, numeral keys operative on said totalizer and differential mechanism unit, and a pair of side plates 70 affording a common support for both of said frameworks, numeral and tabulating keys and tabulator mechanism.

30. In a calculating machine, the combination of a movable platen, a movable master wheel connected therewith by a linkage causing said master wheel to move in the reverse direction from said platen, means adapted to advance said platen step by step, a shaft having a set of arms thereon 80 spirally arranged, link mechanism connecting said shaft and platen, a tabulator key, and a pair of jaws in connection therewith adapted to close upon one of said arms and locate the attached shaft, whereby the 85 operation of a tabulator key will positively locate said platen and master wheel in a position dependent upon the tabulator key operated.

31. In a calculating machine, the combination of a shaft having arms thereon set in spiral arrangement, rollers supported from said arms, a numeral key, a cam connected to said numeral key and adapted to engage one of said rollers and locate said shaft in a 90 position dependent upon said cam, a numeral key of different numerical value, and a cam connected to the last mentioned numeral key adapted to engage the same roller engaged by the first cam to locate said roller in a different position.

32. In a calculating machine, the combination of a shaft adapted to be rotated a differential amount, a set of arms on said shaft spirally arranged, rollers supported 105 between said arms and two differently shaped cams adapted to engage each of said rollers, one of said cams being so shaped as to rotate said shaft a different amount from the rotation resulting from the engagement 110 of the other of said cams with said roller.

33. In a calculating machine, the combination of a set of numeral keys, a shaft adapted to be rotated a differential amount by said keys, a series of spirally arranged 115 rollers on said shaft whereby it may be located, and a set of cams connected to said numeral keys, a cam connected to an even numbered key and a cam connected to an odd numbered key, both engaging one roller, 120 the cams connected to said even numbered keys being adapted to move said rollers to a different extent than the cams connected to the odd numbered numeral keys.

34. In a calculating machine, the combination of a carriage, normally locked feed mechanism normally geared to said carriage, tabulator mechanism including a tabulator key and means controlled thereby for moving the carriage by an actuation of said key, 130

and automatically operating means controlled by said tabulator mechanism for releasing the carriage from the control of its feed mechanism before the tabulating movement of the carriage takes place and without unlocking said feed mechanism and for restoring the carriage to the control of said feed mechanism before the actuated tabulator key starts its return movement in order 10 to lock the carriage by its locked feed mechanism before the carriage is released from the control of said tabulator mechanism.

35. In a calculating machine, the combination of a differential mechanism, a set of 15 numeral keys adapted to operate the same, a decimal carriage, means to bring said decimal carriage to any desired decimal place, said means including a positively operated linkage and a set of tabulator keys one for 20 each decimal order and all adapted to operate said linkage, and an interlock between said tabulator keys and said numeral keys whereby the fact of any tabulator key being depressed prevents the operation of any numeral key and vice versa.

36. In a calculating machine, the combination of a differential mechanism, a set of 30 numeral keys adapted to operate the same, a decimal carriage, means to bring said decimal carriage to any desired decimal place, said means including a positively operated linkage and a set of tabulator keys one for 35 each decimal order and all adapted to operate said linkage, and an interlock between said tabulator keys and said numeral keys whereby simultaneous operation of any two of said keys is prevented.

37. In a calculating machine, the combination of a differential mechanism, a set of 40 numeral keys adapted to operate the same, a decimal carriage, means to tabulate said decimal carriage to any desired decimal order in either direction prior to the insertion of a number by any of said keys, said tabulating means consisting of a positive linkage composed of rigid members, a set of tabulator keys operative on said tabulating linkage, a set of projections one comprised 45 in the key mechanism of each of said tabulator and numeral keys and all in alinement,

a set of pivoted pendants interposed between said projections and adapted to be displaced thereby, and fixed stops to constrain their motion, whereby the depression of any numeral key and the resulting displacement of said pendants will prevent the operation of any tabulator key and vice versa.

38. In a calculating machine, the combination of a decimal carriage, a printing 60 mechanism, a platen adapted to be fed step by step and connected to said decimal carriage by a linkage so that said carriage and platen move in reverse directions, a set of tabulator keys, a locating linkage adapted 65 to locate said decimal carriage and platen simultaneously in a position determined by a particular one of said tabulator keys, and means operated by said locating linkage to rotate said platen and thereby feed the paper 70 upon the operation of any of the tabulator keys.

39. In a calculating machine, the combination of a lateral movable platen, means to write numbers on said platen digit by digit, 75 and means for advancing the same step by step during the writing of said numbers, a paper roll, a support for said paper roll fastened to the framework of the machine, and a paper guide adapted to guide the 80 paper from the stationary roll to the movable platen.

40. In a calculating machine, the combination of a carriage and tabulator mechanism including a contact that moves in unison with the carriage in the movement of the latter in both directions, a tabulator key, and two controlling members controlled by said key and movable thereby toward each other to coact with said contact which is 85 interposed between said members and move the contact and the carriage connected therewith to a predetermined point, the direction of movement of the carriage by an actuation of the tabulator key depending on the 90 position of the carriage before the actuation of the tabulator key takes place.

In witness whereof I have hereunto subscribed my name.

JOHN C. WAHL.
